DOORCHECK

Alex Rose, Cleveland, Ohio

Application June 17, 1932, Serial No. 617,804

3 Claims. (Cl. 292—16)

This invention relates to door checks and more specifically to latching mechanisms for retaining garage doors and the like in their open position.

One of the objects of this invention is to provide a check for garage doors and the like, the latching mechanisms thereof being organized for ready engagement when the door is swung into its open position, and further which is capable of maintaining the door in such position under relatively high wind pressure.

Another object of this invention is to provide a catch in which the door may be readily released without manipulation of any latch or catch mechanism.

Another object of the invention is to provide a door catch which may be mounted upon a garage or similar structure without the necessity of employing a skilled artisan to effect such installation.

Another object of the invention is to construct a door catch which is formed to accommodate the ready repair or renewal of members thereof which are subject to breakage or wear.

Another object of the invention is to provide a door catch, the members thereof being adapted for interchangeable use with similar members which are formed to facilitate the angle of opening at which it is desired to secure the door.

Another object of the invention is to construct a door check which is efficient in operation, durable of construction and economic of manufacture.

Other objects more or less ancillary of the foregoing and the manner in which all the various objects are realized will appear in the following description which, considered in connection with the accompanying drawings, sets forth the preferred embodiment of the invention.

In the drawings—

Figure 1 is an elevational view of a portion of a building structure illustrating the door check embodying the present invention as applied upon such structure.

Figure 2 is a transverse sectional view through the structure taken on the plane indicated by line 2—2 in Figure 1.

Figure 3 is a detail elevational view of the door check shown in Figure 1.

Figure 4 is a side elevational view of the device illustrated in Figure 3.

Figure 5 is a sectional view taken through a portion of the door catch illustrated in Figure 3, the section being taken on a plane indicated

by line 5—5 in Figure 3. A sectional view of the door catch plunger is further included in this illustration being shown therein in its relative position to the door catch.

Figure 6 is a horizontal sectional view of the catch, the section being taken on a plane indicated by the line 6—6 in Figure 4.

Figure 7 is a detailed plan view of a modified form of one of the spring bolts and the supporting frame therefor which comprises one of the members of the catch.

Figure 8 is a transverse sectional view of the same, the section being shown on a plane indicated by the line 8—8 in Figure 7. A sectional view of the door catch plunger is also shown in the figure in its relative position with the catch.

Figure 9 is a front elevational view of a modified form of the catch mechanism.

Figure 10 is a transverse sectional view of the catch shown in Figure 9, the section being taken on a plane indicated by the line 10—10 in Figure 9.

Figure 11 is a perspective view of one form of the door catch plunger embodied in the present invention. This form of plunger is provided to accommodate the securement of the door when opened at substantially a right angle.

Figure 12 is a detailed perspective view of an alternate form of door catch. This form of catch is provided to accommodate the securement of the door when opened at an angle greater than 90°.

Referring to the drawings and particularly Figure 1 thereof, a building structure 10 as shown herein embodies wall portions or stanchions 11 to which the doors 12 are hinged in the usual manner. Upon the walls 11 the door catch 13 is mounted being preferably secured thereon through bolts 14 extending through the walls and secured thereto by nuts drawn against the inner face of the wall structure. As shown the plunger members 15 are mounted upon one of the doors 12 in horizontal alignment with the door catch 13, while the plunger 15a is shown upon the other door. It is to be understood, however, that such arrangement is optional as the arrangement of the parts may be varied to accommodate the structural conditions of the building.

The catch member comprises a housing 16 preferably formed of sheet steel, and as shown, formed with longitudinally extended flanges 17 which are suitably apertured to receive the bolts 14. The body of the housing is rectangular in form and apertured with elongated openings 18

for the reception of supporting lugs or tongues formed in the plunger cradle. The central portion of the housing 16 is provided with an opening 19 to accommodate the re-entrant engagement of the plunger 15.

The spring bolts are supported in cradles 20 which embody a base portion 21, a wall 22 and narrow centrally disposed wall or post 23. The walls 22 and 23 are shouldered to form tongues 10 or lugs 24 which are received in the apertures 18 and riveted therein upon assembly to effect the securement of the cradles within the housing 16. The spring bolts 25 comprise a rectangular block laterally proportioned to slide freely 15 within the housing 16 and of suitable thickness for longitudinal movement within the cradles 20. In the central portion of each of the bolts 25 there is a slot 26, the end walls thereof being coordinated with the posts 23 to limit the longitudinal movement of the bolt. Intermediate the 20 rear wall of the bolts 25 and the end walls 22 of the cradles there are contractile springs which are provided to effect the yielding movement of the bolts within the housings. The 25 cradles 20 are so positioned within the housing 16 that the forward faces of the bolts will lie in contiguous relation in the center of the openings 19. The faces of the plungers are arcuate in form, the forwardmost portion thereof being 30 provided with long sweeping arcs 27 to accommodate the entrance and ready separation of the spring bolts upon application of the effort imposed thereon by the plunger head 28 when the door is secured in its open position. The rearward edges of the plungers are formed with acute 35 radii 29 which grip the inner walls of the plunger head 28 and prevent the dislodgment of the plunger under relatively light application of pressure.

40 As shown in Figures 7 and 8 the side walls of the spring bolts are formed with notched side walls 30 which are arranged for engagement by a pair of stop members or posts 31. In this structure a guideway for the bolts 25 is provided 45 in addition to the shoulders or stops as formed by the slots 26 described in the preceding form. As further illustrated in Figure 7 an adjusting screw 32 is provided in the rear flange 22 of the cradles, the screw being adapted to facilitate the spring tension desired upon the plungers 25.

The embodiment illustrated in Figures 9 and 10 comprises a single spring bolt 25 and includes a depending flange 33 which retains the plunger 55 head 28 and which is employed in substitution for a second plunger 25 as heretofore described.

Referring to Figures 2, 11 and 12 it will be seen that the plunger members are formed of the same headed structure and that the engagement with the catch 15 is effected in the same manner by the use of either. It will be further noted that the extended and angulated neck 34 of the catch 15a will permit a limited movement 60 of the door, that is, an opening at substantially a right angle, while the engagement of the

plunger 15 will permit the door to be revolved to its fully open position.

Although the foregoing description is necessarily of a detailed character, in order that the invention may be completely set forth, it is to be understood that the specific terminology is not intended to be restrictive or confining, and that various rearrangements of parts and modifications of structural detail may be resorted to without departing from the scope or spirit of the invention as herein claimed.

I claim:

1. A latch assembly for hinged garage doors and the like comprising in combination with a plunger latch: a housing adapted to be secured to a support adjacent the door, a cradle secured to said housing, a slotted bolt mounted for snug sliding movement in said cradle, said cradle being provided with means engaging in the bolt slot for limiting the longitudinal sliding movement of the bolt, a spring in rear of said bolt for normally urging it toward latching position, the latch extremity of said bolt being formed with an arcuate end surface, said housing being apertured adjacent the arcuate extremity of the bolt, 20 said plunger latch being secured to the door and having an enlarged head adapted to retract and be releasably engaged by said bolt.

2. A latch assembly for hinged garage doors and the like comprising in combination with a plunger latch: a bolt guiding and supporting cradle, a housing adapted to support said cradle at the desired angle relatively to the door, a pair of slotted bolts mounted for snug sliding movement in said cradle toward and away from one another, said cradle being provided with projections which engage in the slots of the bolts and limit the longitudinal sliding movement of the bolts, springs disposed between the rear ends of said bolts and the rear end walls of the cradle for normally urging the bolts to latching position, means for adjusting the tension of said springs, the adjacent end faces of the bolts being formed with arcuate surfaces, said plunger latch being secured to a door and having a relatively flat shank and an enlarged substantially oval-shaped head adapted to engage said surfaces and retract the bolts and be releasably held thereby.

3. A latch assembly for hinged garage doors and the like comprising a pair of bolt-guiding and supporting frames, a bracket housing adapted to be secured to a support adjacent a door and support said frames at the desired angle relatively to a door, a pair of coacting latch bolts slidably mounted in said frames and having arcuate end faces, springs in rear of said bolts for normally urging the latter to latching position, means for adjusting the tension of said springs, each of the bolts being formed with a recess or cut-out portion, and limit stops associated with the housing and adapted to engage in said recesses or cut-out portions for limiting movement of said bolts toward one another to thereby maintain their latch ends spaced apart to facilitate reception of a latch plunger.

ALEX ROSE.
